WILLIAM MARSHALL AND FREDERICK KIEHLER OF DETROIT, MICHIGAN, ASSIGNEES
TO BRIGGS MANUFACTURING COMPANY, OF DETROIT, MICHIGAN, A CORPORATION OF MICHIGAN.

VEHICLE DOOR LATCH.

Application filed February 16, 1925. Serial No. 9,681.

This invention relates generally to latches designed particularly for use with vehicle doors and consists of certain novel features of construction, combinations and arrangements of parts as will be more fully described and particularly pointed out in the appended claims.

In the accompanying drawings;

Figure 1 is a side elevation of a latch embodying our invention applied to a vehicle door.

Figure 2 is a horizontal sectional view taken on the line 2—2 of Figure 1.

Figure 3 is a vertical sectional view taken on the line 3—3 of Figure 1.

Figure 4 is a top plan view of the latch bolt.

Figure 5 is a side elevation thereof.

Figure 6 is a top plan view of the case plate.

Figure 7 is a horizontal section view through a slightly modified form of construction.

Figure 8 is a side elevation of another modified construction.

Figure 9 is a detail top plan view of the bolt shown in Figure 8.

Heretofore the case plates of door latches have been mounted upon the inner sides of the doors and the locking bolts of such latches have been retracted from the outside of the doors by rotatable spindles extending through the doors. With such constructions, the pillars of the doors were usually quite large in cross section to accommodate the spindles, which ordinarily were spaced several inches from the free edges of the doors, thus the vision of the occupants of the vehicle was limited. Furthermore when the outside operating means extended through the door, the vertically movable glass panel usually provided in the doors had to be relatively narrow so that the movement thereof would not be interrupted by the operating means for the latch bolt. To overcome these objectionable features, I have provided a lock having a case plate that may be attached to a door pillar having a very small cross section. Moreover both the case plate and the locking bolt preferably straddle the guide-way for

the vertically movable glass panel, hence the occupants of the vehicle will have an increased vision and a wider glass panel may be employed.

Referring now to the drawings in which like characters of reference designate corresponding parts throughout the several views, the numeral 1 designates a door, preferably of a vehicle body, having a pillar 2 provided at its inner edge with a channel-shaped portion 3 which constitutes a run-way for a vertically movable glass panel 4.

In order that a suitable latch may be mounted and operated upon the pillar 2 without interfering with the vertical movement of the glass panel 4, we preferably provide a case plate 5 that is preferably U-shape in cross section and that preferably straddles the channel-shaped guide-way 3. Straddling this case plate 5 and the guide-way 3 for the glass panel is a reciprocatory bolt 6 that is also preferably substantially U-shape in cross section. As shown, the shank sections 7 and 8 respectively of the bolt slidably engage the inner and outer sections 9 and 10 respectively of the case plate 5, while the transversely extending portion 11 constitutes the head of the bolt and is adapted to engage the striker plate 12 of a suitable keeper upon the door jamb of the vehicle body. It will be noted that this portion 11 extends at substantially right angles from the shank 8 and has a rounded portion 11' that extends between this straight portion 11 and the shank 7. Thus this rounded portion facilitates the engagement of the bolt with the opening in the door jamb 2. Any suitable means such as the lugs 13 struckout from the case plate 5 may be employed for guiding the bolt 6, while a helical spring 14 anchored upon the inner section 9 of the case plate is preferably used to normally hold the bolt in projected position.

For retracting the bolt 6 against the tension of the spring 14, we preferably provide a suitable roll-back 15 that is adapted to be operated from the outside of the door, and a pivoted lever 16 that is adapted to be operated from the inside of the door. As shown, the roll-back 15 is engageable with a shoulder 17 of the outer shank section 8 of the bolt 100

and is provided with a hub 18 that is journaled in aligned openings in the outer section 10 of the case plate and a cover plate 19 secured thereto. Any suitable means (not shown) may be engaged with the square opening 20 in the hub 18 for rocking the roll-back 15 against the shoulder 17 for retracting the bolt. The lever 16 is preferably pivoted at its lower end to the inner section 9 of the case plate, below the bolt shank 7 and is engageable with the pin 22 on the section 7 of the bolt for retracting the latter. To prevent the lever 16 from rattling, we preferably provide a spring 23 that is anchored upon a pin 24 extending from the inner section 9 of the case plate and is provided with suitable arms 26 and 27 respectively. As shown, the arm 27 bears against the inner edge of the lever 16, while the arm 26 is secured to the offset portion 25 of the case plate. Thus, with this construction, the lever 16 may be operated against the lug 22 to retract the bolt without affecting the roll-back 15, and the latter may in turn be operated against the shoulder 17 without affecting the lever 16. The spring 14 will always exert a pressure through the lug 22 on the shank section 7 of the bolt against the lever 16 so that the latter will normally be in operative position to retract the bolt. Likewise the spring 14 will exert a pressure through the shoulder 17 of the bolt against the roll-back 15 and will normally hold the latter in operative position against a flange 28 extending laterally outwardly from the forward edge of the cover plate 19.

In order that the outside operating means may be rendered inoperative from the inside of the door, we preferably provide a cam 29 that is adapted to be swung downwardly in an arcuate shaped recess 30 at the rear end of the inner shank section 7 of the bolt and engaged with a lateral flange 31 of the inner section 9 of the case plate. As shown, this cam 29 is rigidly secured to a pivot pin 30 that is journaled in the cover plate 25 and inner section 9 of the case plate and is adapted to be rotated by a suitable lever 32 located upon the inner side of the cover plate 32'. Thus, when the cam 29 is in engagement with the section 7 of the bolt and the flange 31 of the cover plate, the bolt cannot be retracted by either the lever 16 or the roll-back 15.

In order that the retracting means for the bolt may be rendered inoperative from the outside of the door, we preferably provide a cam 33 that is engageable with an arcuate shaped recess 34 in the outer shank section 8 of the bolt. As shown, this cam 33 has a hub that is journaled in the cover plate 19 and outer section 10 of the case plate and is adapted to be actuated by a key operated shank 36 of a suitable auxiliary lock 37.

In Figure 7, we have shown a slight modification in which the head 40 of the bolt is preferably provided with a vertical inwardly off-set portion 41 providing a shoulder 42 that is adapted to engage the striker plate 43 of a suitable keeper upon the door jamb of the vehicle body to hold the door in partially closed position.

In Figures 8 and 9, we have shown a slight modification, in which the inner shank section 50 of the bolt is preferably provided with a pivoted portion 51. As shown, this portion 51 is preferably provided at its forward end with a rounded head 52, and a reduced neck 53 that engage correspondingly shaped recesses 54 and 55 respectively in the outer section 50 of the bolt. Thus, this hinge joint will prevent the inner and outer sections of the bolt from binding and will relieve any friction therebetween.

From the foregoing description it will be readily apparent that a latch of this type may be mounted upon a door pillar having a very small section, consequently the vision of the occupants of the vehicle is materially increased. Moreover, the bolt straddles the guide-way for the glass panel, hence the movement of the outside operating means will not interrupt the vertical movement of the glass panel, and it will also be apparent that the outside operating means and inside operating means may be independently operated for retracting the bolt.

While it is believed that from the foregoing description, the nature and advantages of our invention will be readily apparent, we desire to have it understood that we do not limit ourselves to what is herein shown and described and that such changes may be resorted to when desired as fall within the scope of what is claimed.

What we claim as our invention is:

1. In a latch, the combination with a case plate having a laterally extending flange, of a bolt straddling the case plate, means normally holding the bolt in projected position, means for retracting the bolt against the tension of the yieldable means, and means for rendering the retracting means inoperative including a member adapted to swing between one section of the bolt and the flange aforesaid of said case plate.

2. A latch for a door of the type having a runway for a vertically movable glass panel comprising a latch unit assembly having a case plate of U-shape in cross section for straddling the runway, one side of said case plate being provided with a flange for attachment to the door, the other side of said case plate being provided with a lateral flange, a latch bolt slidably mounted upon said case plate, actuating means for said bolt carried by said case plate, and means for rendering said actuating means inoperative in-

cluding a cam movable between said bolt and the second mentioned lateral flange of said case plate.

3. A latch for a door of the type having a runway for a vertically movable glass panel comprising a case plate provided with a lateral flange, a latch bolt slidably mounted upon said case plate, actuating means for

said bolt carried by said case plate, and means for rendering said actuating means inoperative, including a cam movable between said bolt and the lateral flange of said case plate. ¹⁰

In testimony whereof we affix our signatures.

WILLIAM MARSHALL.
FREDERICK KIEHLER.
